UNITED STATES PATENT OFFICE.

WILLIAM T. MERZENICH, OF MINNEAPOLIS, MINNESOTA, ASSIGNOR TO GEORGE M. WATTERS, OF MINNEAPOLIS, MINNESOTA.

PRIMER FOR INTERNAL COMBUSTION ENGINES.

1,303,353.

Specification of Letters Patent. Patented May 13, 1919.

Application filed December 1, 1916. Serial No. 134,312.

To all whom it may concern:

Be it known that I, WILLIAM T. MERZENICH, a citizen of the United States, residing at Minneapolis, in the county of Hennepin 5 and State of Minnesota, have invented certain new and useful Improvements in Primers for Internal-Combustion Engines; and I do hereby declare the following to be a full, clear, and exact description of the invention, 10 such as will enable others skilled in the art to which it appertains to make and use the same.

My invention has for its object to provide an extremely simple and highly efficient 15 primer for internal combustion engines; and, to this end, it consists of the novel devices and combinations of devices herein-after described and defined in the claims.

In the accompanying drawings, which 20 illustrate the invention, like characters indicate like parts throughout the several views.

Referring to the drawings:—

Figure 1 is a fragmentary side elevation of an automobile having the invention 25 incorporated therein;

Fig. 2 is a front elevation of the reservoir of the primer removed from the instrument-board;

Fig. 3 is a vertical section taken on the 30 line 3—3 of Fig. 2; and

Fig. 4 is a vertical section taken on the irregular line 4—4 of Fig. 3.

The automobile illustrated, for the purpose of showing the invention applied in 35 working position, is of the well known Ford type and it is only necessary to note the following parts thereof, to wit:—running gear 5, body 6, front seat 7, instrument-board 8, wind shield 9, internal combustion engine 40 10, fuel intake manifold 11, carburetor 12, gasoline supply tank 13 located under the seat 7, and gravity fuel feed pipe 14, which leads from the tank 13 to the carburetor 12. It is, of course, understood that the improved primer may be applied to any other 45 make of automobile.

Referring now to the improved primer, the numeral 15 indicates an annular casing secured to the instrument-board 8 and affording a gasoline reservoir 16. This casing 15 has a transparent face plate 17 of glass, through which the gasoline supply in the reservoir 16 may be observed. An annular retaining ring 18 secured to the casing 55 15 by screws 19, holds the face plate 17 in

position with a gasoline-tight joint there-between. In the back of the casing 15, is formed a vertically disposed conduit 20 having, at its extremities, upper and lower horizontally disposed branch conduits 21 and 22, 60 respectively. Diametrically opposite ports 23 and 24 connect the branch conduits 21 and 22, respectively, with the reservoir 16. Needle valves 25 and 26 are provided for independently controlling the branch conduits 21 and 22, with respect to its ports 23 and 24. These needle valves 25 and 26 are screwed, from the face of the casing 15, into seats formed therein and which are axially aligned with the respective branch conduits 70 21 and 22. The gasoline in the reservoir 16 is indicated at Z.

The lower end of a pipe 27 taps the feed supply pipe 14 close to the carburetor 12 and its upper end is screwed into a boss on 75 the back of the casing 15 and has communication with the reservoir 16, at the top thereof, through a conduit 28 formed in said casing. The upper end of a pipe 29 is screwed into a boss on the back of the casing 15 in 80 axial alignment with the branch conduit 22 and has communication with the conduit 20 and branch conduit 22. The lower end of the pipe 29 is arranged to discharge into the fuel intake manifold 11, close to the arms 85 thereof. It is important to note that the reservoir 16 is located on the instrument-board 8 at an elevation considerably above the fuel intake manifold 11, so that the gasoline in said reservoir will feed by gravity 90 said fuel intake manifold.

The operation of the improved primer may be briefly described as follows:—

By opening the valve 25, while the engine is running, a partial vacuum is created in 95 the reservoir 16, under the suction stroke of the engine, through the port 23, branch conduit 21, conduit 20, pipe 29 and intake manifold 11. This partial vacuum in the reservoir 16 will draw gasoline from the tank 13 into the reservoir 16, through the pipes 14 and 27 and conduit 28. When the reservoir 16 is full of gasoline, which may be observed through the transparent face 17 of the casing 15, the valve 25 may be closed. In starting the engine, the valve 26 is opened 105 sufficiently to allow a small amount of gasoline to be fed by gravity through the port 24, branch conduit 22, pipe 29 and into the fuel intake manifold 11; from thence, it will 110

be drawn into the cylinders of the engine, under the suction stroke of the engine.

In case the reservoir 16 is empty, when the engine is to be started, it will take several strokes of the engine to draw a supply of gasoline into the reservoir, before the same can be fed to the fuel intake manifold.

Primarily the improved primer is for use 10 in starting internal combustion engines in cold weather, but it is, of course, understood that the same may be used at any other time, in case it is hard to start the engine; for instance, when the spark is weak and a 15 richer fuel mixture is desired. The word "gasoline" is herein used in a broad sense to cover any suitable liquid fuel.

The above described invention, while extremely simple and of small cost to manufacture, has, in actual usage, proven highly 20 efficient for the purpose had in view.

What I claim is:—

1. A primer for internal combustion engines including a reservoir, a fuel supply 25 conduit leading to the reservoir from a suitable source of supply, a fuel feed conduit having at its receiving end two branch con-

duits opening into the reservoir, the one above the liquid level and the other below the same, the latter of said branch conduits 30 and the fuel feed conduit arranged to permit a gravity feed to the intake of the engine, and two valves for independently closing said two branch conduits.

2. A primer for internal combustion engines including a reservoir, a constantly open fuel supply conduit leading to the reservoir above the liquid level from a suitable source of supply, a fuel feed conduit having at its receiving end two branch conduits 35 opening into the reservoir, the one above the liquid level and the other below the same, the latter of said branch conduits and the fuel feed conduit arranged to permit a gravity feed to the intake of the engine, and two 40 valves for independently closing said two branch conduits.

In testimony whereof I affix my signature in presence of two witnesses.

WILLIAM T. MERZENICH.
